UNITED STATES PATENT OFFICE.

JOSEPH W. KENNA, OF CHICAGO, ILLINOIS, ASSIGNOR TO WILLIAM I. BUNKER AND CHARLES L. MILLER, BOTH OF SAME PLACE.

DESIGN FOR A BRACKET FOR SPRINGS.

SPECIFICATION forming part of Design No. 16,571, dated March 16 1886.

Application filed October 31, 1885. Serial No. 181,545. Term of patent 14 years.

To all whom it may concern:

Be it known that I, JOSEPH W. KENNA, a citizen of the United States, residing at Chicago, Illinois, have invented and produced a Design for a Bracket, of which the following is a specification.

The leading feature of my design is a bracket having two substantially parallel side ribs, A A, one at or upon each edge of a flat plate or web, B, terminating in a base-plate, C. The base-plate extends out at either side, so as to have its ends c c farther apart than the distance between the outer ends of the ribs a a, and the ribs are slightly curved and the flat web gradually widened near the base-plate.

The parallel ribs at or upon the edges of the flat plate or web and terminating in the base-plate present the design.

I claim—

The design for a bracket herein shown and described, consisting of two substantially parallel side ribs, one at or upon each edge of a flat plate or web, and terminating in a base-plate, substantially as described.
